UNITED STATES PATENT OFFICE.

WILLIAM J. SCHLACKS, OF CHICAGO, ILLINOIS, ASSIGNOR TO McCORD AND COMPANY, OF CHICAGO, ILLINOIS, A CORPORATION OF DELAWARE.

FORCE-FEED LUBRICATOR

1,307,988.

Specification of Letters Patent. Patented June 24, 1919.

Application filed July 20, 1918. Serial No. 245,948.

To all whom it may concern:

Be it known that I, WILLIAM J. SCHLACKS, a citizen of the United States, residing at Chicago, in the county of Cook and State of Illinois, have invented certain new and useful Improvements in Force-Feed Lubricators; and I do hereby declare the following to be a full, clear, and exact description of the invention, such as will enable others skilled in the art to which it appertains to make and use the same.

My invention relates to force feed lubricators of the diaphragm displacement type, and while especially designed for use in locomotive lubricator service, is, nevertheless, adapted for various other lubricator purposes. The invention resides in an improved arrangement of diaphragms and immediately associated coöperating parts whereby decided improvements are obtained from a manufacturing point of view, from the point of durability and from the point of efficiency in operation. Generally stated, the invention consists of the novel devices and combinations of devices herein-after described and defined in the claims.

In the preferred form of the improved lubricator illustrated in the accompanying drawings, the pumping action is produced by slight vibrations or reciprocations of a differential diaphragm structure, which structure comprises two diaphragms having exposed areas of different extent. The large diaphragm is subject to pressure pulsations produced, for instance, by the varying pressure in one end of an engine cylinder, and the smaller diaphragm acts as an oil displacing element, and, in the customary application for lubricating an engine cylinder, would be subject to steam passage pressure. The two diaphragms, by an axial strut or tie post, are caused to partake of common vibratory movements. Other important features, such for example, as the arrangement whereby the hot live steam which acts upon the large diaphragm, is prevented from overheating the oil in the lubricator reservoir, are provided.

In the drawings, like characters indicate like parts throughout the several views. Referring to the drawings:

Figure 1 is a vertical section taken through the improved lubricator on the line 1—1 of Fig. 3;

Fig. 2 is a vertical section taken through the lubricator on the line 2—2 of Fig. 3;

Fig. 3 is a horizontal section taken on the line 3—3 of Fig. 1; and

Fig. 4 is a fragmentary detail in vertical section on the line 4—4 of Fig. 3.

The oil reservoir is preferably made up of a heavy glass cylinder 4, a base 5 and a cap 6, the said base and cap being connected by a suitable nut-equipped rod 7, which, as is usual, seats the ends of the cylinder 4 against suitable gaskets or packings 8 set into the said members 5 and 6. The base 5 has an externally threaded lower portion 9 of reduced diameter, and onto which is screwed a two-part member or casting 10—11 that affords the diaphragm housing. This housing, by means of nut-equipped studs 12, or any other suitable devices, is adapted to be anchored to any suitable part of a locomotive or other engine. The sections of the two-part housing 10—11 are detachably connected by threaded engagement at 13.

The lower or larger diaphragm 14 is a flat and very stiff but slightly resilient metal disk, and at its peripheral edge, it is clamped between an internal shoulder 11a of the member 11 and a spacing washer 15 that is set into the member 10 and seated against shoulder 10a thereof. Of course, there is an air or steam-tight joint at 11a.

The upper or smaller diaphragm 16 is like the diaphragm 14, except that it is of less diameter and has less exposed area. It is clamped between a shoulder on the member 10 and a washer 17 set into the base member 5, and there is, of course, a fluid-tight joint between the said members 5, 10 and 17.

The two diaphragms 14 and 16 are axially connected by a strut or post 18 which has upper and lower end threaded studs 19 and 20 that are passed, respectively, through axial perforations in the diaphragms 16 and 14. Nuts 19a and 20a on the studs 19 and 20, respectively, clamp the respective diaphragms 16 and 14 tightly against the ends of the strut 18. A suitable spring normally holds the lower end of the threaded stud 20 against an axial hub 11b of the member 11. This spring may take various forms, but preferably, as shown, is in the form of a spring cross bar 21. The central portion of the spring bar 21 bears against a

shoulder 18^a of the strut 18 and has a large passage through which the reduced portion of the strut is passed. The ends of said spring are clamped between the spacing 5 washer 15 and an undercut shoulder of the member 10. Obviously, this spring bar 16 yieldingly presses the strut and hence, the axial portions of the two diaphragms downward as far as permitted by engagement 10 of the stud 20 with the hub 11^b.

It will be noted that there is considerable space between the two diaphragms which affords an air chamber 23 within the member 10. This air chamber 23, for an important reason, is connected to the atmosphere through radial ventilating holes 24.

A live steam chamber 25 is formed in the member 11 immediately below the lower and larger diaphragm 14; and this chamber 25 20 is, in practice, connected to the cylinder steam passage of the engine, or other source of variable pressure, through a live steam pipe 26.

An oil chamber 27 is formed in the base 5 25 immediately above the upper and smaller diaphragm 16; and this oil chamber 27 is connected to the interior of the oil reservoir, through a check valve-equipped oil intake conduit formed within the base member 5, 30 and, as shown, comprises an oil duct 28 (see Fig. 2), a check ball chamber 29 (see Figs. 2 and 4) and an oil duct 30 with upwardly extended tube 31, (see Fig. 4). In the check ball chamber 29 is a gravity-seated check 35 ball or valve 32 that permits a flow of oil from the oil reservoir into the oil chamber 27 but checks or prevents a reverse flow. This check ball therefore acts as the intake valve of the pump mechanism.

40 Oil chamber 27 is adapted to be connected to the steam supply pipe of the engine or other part or device to receive the lubricant through a check valve-equipped oil delivery conduit, which, as shown, is constructed and 45 arranged as follows:

In the axial portion of the base member 5 is a check ball chamber 33, in the lower end of which is a threaded plug 34 having an axial oil duct 35 that is normally closed by a 50 gravity-seated check ball or valve 36. The upper portion of chamber 33 has an extended oil delivery duct 37 that extends through a projecting externally threaded nipple 38 and is connected to a tubular pipe coupling 55 39, by means of a clamping nut 40. The oil pipe coupling 39 may be assumed to be connected by an extended pipe not shown, to the steam supply pipe or cylinder of an engine, the cylinder of which is connected to the live 60 steam pipe 26.

In a pump of this character, the oil displacing movement of the diaphragm may be and should be very slight, and, in practice, I have found that it may be as slight as 65 2/1000 of an inch, but for illustration we

may assume it to be as much as 1/32 of an inch, in which case, when the stud 20 engages the hub 11^b, the diaphragm should be flexed downward approximately 1/64th of an inch at the central portions, and when the 70 upper stud 19 strikes against the plug 34, the said diaphragm should be then flexed upward about 1/64th of an inch from the respective planes of their perimeters or clamping marginal portions. Otherwise 75 stated, regardless of what may be the maximum diaphragm movement, such movement should be evenly divided on opposite sides of the said respective plane, so as to thereby obtain the absolute minimum amount of 80 shortening and lengthening of the radial lines of the diaphragm.

With the lubricator connected to an engine, as above described, there will be constant live steam or steam chest pressure 85 against the oil, and hence, against the upper or smaller diaphragm 16, and there will be a pulsation of steam pressure against the lower or larger diaphragm 14 due to the fact that the pressure in the cylinder to which 90 steam pipe 26 is connected, will vary between maximum live steam pressure and a diminishing pressure down to the point of exhaust from the cylinder. In view of the relatively large area of diaphragm 14, the 95 two diaphragms will be pressed upward when said larger diaphragm is subjected to maximum live steam or fluctuating fluid pressure. The two diaphragms will be pressed downward by a spring bar 21 acting 100 on post 18; and on the other hand, the two diaphragms will be pressed downward by spring bar 21 acting on post 18 when the said larger diaphragm 14 is subjected to minimum live steam or fluctuating fluid 105 pressure. The vibratory movements thus imparted to the smaller diaphragm 16 produce an oil pumping action which is in proportion to the speed of the engine.

The oil must, of course be in contact with 110 the upper or smaller diaphragm, and hence, it is highly important that this upper diaphragm be not heated to excessive temperature by the steam which comes into contact with the larger or lower diaphragm. In 115 the arrangement described, the upper diaphragm is kept cool and overheating of the oil is prevented by the circulation of air between the two diaphragms, around the strut and within the chamber 23 and through the 120 air ports 24. The position of the spring between the diaphragm is important because it is desirable to reduce to a minimum the volume of oil contained in the oil chamber of the pump mechanism, and for that reason, 125 to reduce the said oil chamber to the smallest possible oil containing capacity.

It is highly important also to avoid the use of corrugated metal diaphragms, and this can be done only where the diaphragm 130

movement is very slight, as in my arrangement above described. Corrugated metal diaphragms, under high pressure, such as that to which the diaphragms of this lubricator are subjected in practice, would collapse and would not be positive in their action, and in collapsing, would suffer such fiber stress as soon to cause their disruption and failure. It is obvious that corrugated metal diaphragms would tend to straighten out under high pressure or load. In my improved arrangement, the diaphragms have such slight movement that they may not only be made flat or without corrugations, 15 but may be made of quite heavy sheet metal, such as steel or a suitable alloy of metals.

What I claim is:

1. In a force feed lubricator, oil pumping means including differential diaphragms, 20 the larger of which is subject to pressure pulsations and the smaller of which acts as an oil displacing and transmitting element, the said diaphragms being positively connected at their central portions for common vibratory movements.

2. In a force feed lubricator, oil pumping means including differential diaphragms, the larger of which is subject to pressure pulsations and the smaller of which acts as 30 an oil displacing element, the said diaphragms being positively connected at their central portions for common vibratory movements, said diaphragms having a flexing movement from the one side to the other 35 of the planes of their respective rims.

3. In a force feed lubricator, oil pumping means including differential diaphragms, the larger of which is subject to pressure pulsations and the smaller of which acts as 40 an oil displacing element, the said diaphragms being positively connected at their central portions for common vibratory movements, the space between said diaphragms being connected to the atmosphere 45 for the circulation of air.

4. In a force feed lubricator, oil pumping means including differential diaphragms, the larger of which is subject to pressure pulsations and the smaller of which acts as 50 an oil displacing element, the said diaphragms being positively connected at their central portions for common vibratory movements, an oil reservoir, an oil pump chamber opening against said small diaphragm, a conduit connecting said oil reservoir to said oil chamber, an oil delivery conduit extending from said oil chamber, and check valves in the said two conduits co-operating with said small diaphragm in the 60 pumping action.

5. In a force feed lubricator, oil pumping means including differential diaphragms, the larger of which is subject to pressure pulsations and the smaller of which acts as 65 an oil displacing element, the said dia-

phragms being positively connected at their central portions for common vibratory movements, an oil reservoir, an oil pump chamber opening against said small diaphragm, a conduit connecting said oil reservoir to said oil chamber, an oil delivery conduit extending from said oil chamber, and check valves in the said two conduits co-operating with said small diaphragm in the pumping action, the space between said two 70 diaphragms being open to the atmosphere for the circulation of air.

6. In a force feed lubricator, oil pumping means including differential diaphragms, the larger of which is subject to pressure 80 pulsations and the smaller of which acts as an oil displacing element, the said diaphragms being positively connected at their central portions for common vibratory movements, and a spring exerting a force in 85 one direction on the said two diaphragms.

7. In a force feed lubricator, the combination with a casing, of a pair of spaced differential diaphragms mounted in said casing with fluid-tight joints at their margins, the 90 larger of said diaphragms being subject to pressure pulsations and the smaller of said diaphragms acting as an oil displacing element, and a strut positively spacing and positively connecting the axial portions of 95 said two diaphragms.

8. In a force feed lubricator, the combination with a casing, of a pair of spaced differential diaphragms mounted in said casing with fluid-tight joints at their margins, the 100 larger of said diaphragms being subject to pressure pulsations and the smaller of said diaphragms acting as an oil displacing element, and a strut positively spacing and positively connecting the axial 105 portions of said two diaphragms, and stopping means limiting the movements of said diaphragms to positions approximately equidistant on opposite sides of the planes of the respective peripheral portions.

9. In a force feed lubricator, the combination with a casing, of a pair of spaced differential diaphragms mounted in said casing with fluid-tight joints at their margins, the larger of said diaphragms being subject 115 to pressure pulsations and the smaller of said diaphragms acting as an oil displacing element, and a strut positively spacing and positively connecting the axial portions of said two diaphragms, and valve mechanism 120 co-operating with said small diaphragm in the pumping action.

10. In a force feed lubricator, the combination with a casing, of a pair of spaced differential diaphragms in the form of 125 smooth flat metal disks and secured in said casing with fluid-tight joints at their peripheral portions, one of said diaphragms being subject to pressure pulsations and the other acting as an oil displacing element, 130

the said diaphragms being movable from one side to the other of the planes of the respective peripheral portions, and a strut positively connecting the axial portions of 5 the said two diaphragms for common vibratory movements in both directions.

11. In a force feed lubricator, the combination with a casing, of a pair of spaced differential diaphragms in the form of 10 smooth flat metal disks and secured in said casing with fluid-tight joints at their peripheral portions, one of said diaphragms being subject to pressure pulsations and the other acting as an oil displacing element, 15 the said diaphragms being movable from one side to the other of the planes of the respective peripheral portions, a strut positively connecting the axial portions of the said two diaphragms for common vibratory 20 movements in both directions, and a spring located in the space between said two diaphragms acting on said strut, and at its ends anchored to said casing.

12. In a force feed lubricator, the combination with a casing, of a pair of spaced 25 differential diaphragms in the form of smooth flat metal disks and secured in said casing with fluid-tight joints at their peripheral portions, one of said diaphragms being subject to pressure pulsations and the 30 other acting as an oil displacing element, the said diaphragms being movable from one side to the other of the planes of the respective peripheral portions, a strut positively connecting the axial portions of the 35 said two diaphragms for common vibratory movements in both directions, and the said space between said diaphragms being open to the atmosphere for the circulation of air.

In testimony whereof I affix my signature in presence of two witnesses.

WILLIAM J. SCHLACKS.
